Design No. 13,348, dated October 24, 1882.

13,348.

Oct 24 - 1882

UNITED STATES PATENT OFFICE.

JOHN GLEN, OF BROOKLYN, NEW YORK.

DESIGN FOR A PRINTED FABRIC.

SPECIFICATION forming part of Design No. 13,348, dated October 24, 1882.

Application filed September 26, 1882. Term of patent 3½ years.

To all whom it may concern:

Be it known that I, JOHN GLEN, of Brooklyn, Kings county, in the State of New York, have invented a new and original Design for Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

15 It consists in the representation of sprays of flowers, as will hereinafter appear.

Referring to the illustration, A, B, and C represent sprays of flowers, which are combined and repeated upon the ground of the fabric to form the pattern; but the pattern may 20 be formed by repeating the flowers A or B or C, or by combining and repeating the flowers A and B, or A and C, or B and C.

The fabric may be produced in any preferred 25 variety or combination of colors for giving a desirable effect to the design.

What I claim, and desire to secure by Letters Patent, is—

1. The design for printed and other fabrics, consisting of the sprays of flowers A, substantially as set forth. 30
2. The design for printed and other fabrics, consisting of the sprays of flowers B, substantially as set forth.
3. The design for printed and other fabrics, consisting of the sprays of flowers C, substantially as set forth. 35
4. The design for printed and other fabrics, consisting of the sprays of flowers A and B, substantially as set forth.
5. The design for printed and other fabrics, 40 consisting of the sprays of flowers A and C, substantially as set forth.
6. The design for printed and other fabrics, consisting of the sprays of flowers B and C, substantially as set forth. 45
7. The design for printed and other fabrics, consisting of the sprays of flowers A, B, and C, substantially as described and shown.

JOHN GLEN.
